UNITED STATES PATENT OFFICE.

JACOB MAZER, OF PITTSBURGH, PENNSYLVANIA.

SOUND-ABSORBING METHOD AND MATERIAL.

Application filed June 27, 1918. Serial No. 242,272.

To all whom it may concern:

Be it known that I, JACOB MAZER, a citizen of the United States, and resident of Pittsburgh, in the county of Allegheny and State of Pennsylvania, have invented a new and useful Improvement in Sound-Absorbing Methods and Material; and I do hereby declare the following to be a full, clear, and exact description thereof.

10 My invention relates to an improved sound-absorbing material.

The object of my invention is to provide a sound-absorbing material for halls, auditoriums or other enclosures and adapted to 15 be used, without change of structure, as a surface material for walls, ceilings and the like, or, between walls, ceilings and floors and the like.

For the first-mentioned purpose, this improved sound-absorbing material would be applied on the walls, ceilings and other boundary surfaces of rooms in such quantities and in such position as might be found necessary to correct the defective conditions for 25 hearing in an auditorium or other enclosure, or would be applied during the construction of an auditorium or other enclosure, after determining by proper computations, the position and amount of the said sound 30 absorbing material required.

In addition to improving the acoustics within the room, this material greatly reduces the amount of sound transmitted from extraneous sources into the room.

35 For the second-mentioned purpose, namely the application of the improved sound-absorbing material between the walls, ceilings and floors and the like, it would serve only to prevent the transmission of sounds 40 through the walls, ceilings, floors and the like.

My invention aims particularly to provide sound absorbing material having predetermined and controllable sound-modifying effect which may be selected and controlled, and which is produced by surface apertures which are in free communication with the room or other space where the acoustics are to be controlled. The surface 45 apertures may be formed in the material in advance of its installation, or may be formed in the material after the material has been placed in position. This general aspect of my invention is capable of being put to use

with a great variety of substances and with 55 many different arrangements of apertures, some of which are described below.

This invention differs from my previous Patent No. 1,172,379 in that the improved construction herein provided for, is composed 60 of solid or at least comparatively rigid material, as distinguished from loose substances in the nature of felt, and has a series of surface apertures which has a uniform sound-absorbing capacity per unit of area. The 65 individual apertures, in some embodiments of my invention, may be regularly shaped, uniform in size, and of much greater length than width. In other embodiments, as for example in those shown in Figs. 9 and 10 of 70 the accompanying drawing, the individual apertures are of different sizes and are distributed more or less irregularly, but always in such a manner as to give a definite and predetermined sound-modifying effect per 75 square foot, square yard, or other unit of exposed surface. This provision of uniform sound-absorption per unit of area makes it possible to calculate accurately the amount 80 and precise structure of the material needed for any particular case, and to know in advance, and independently of the skill of the workmen, just what result will be produced by any particular element constructed according to my invention.

85 It is commonly known by students of the behavior of sound that absorption of part of the energy of the sound takes place at each impact of the sound wave with a surface and that the sound is reflected from the 90 surface at an angle equal to the incident angle. All other factors remaining equal, an increase in the rate of absorption of a sound is brought about by decreasing the distance between the surfaces from which it 95 is repeatedly deflected. Therefore by providing long narrow apertures, the length of which is considerably greater than the width of the openings, I have a construction that is highly sound-absorbing, since it will cause 100 a rapid decay of the sound even though the materials of which it is composed and which form the walls of the apertures, are not themselves highly sound-absorbing.

105 It follows also that if the apertures just described, communicate with other openings or apertures within the sound-absorbing material, the process of sound absorption will

be increased in such manner that the opportunities are still more remote for a sound to emerge at the surface where it entered the aperture.

5 I have found that any material can be made to absorb a large percentage of sound if its construction is such that when the sound strikes it a great number of impacts must take place within a very short period 10 of time. This is because, as previously mentioned, a definite absorption of sound takes place at each impact.

Fig. 1 shows one type of the improved 15 acoustic material; Fig. 2 shows an enlarged section of one of the apertures in said material; Figs. 3 and 3^a show enlarged sections of apertures in two varieties of another form of the material; Fig. 4 shows still another form of the material; Figs. 5 20 to 12 show still other forms of the device.

In the form of my invention illustrated 25 in Fig. 1, the material is shown to consist of a block 1 of originally plastic material and provided with a number of apertures 2 penetrating into the block from one face, and also showing a number of apertures 3 30 penetrating in from another face.

Fig. 2 of the accompanying drawings 35 shows an enlarged view of a section of one of the multitude or series of tube-like apertures with which the material shown in Fig. 1 is provided. The particular section shown has width of aperture larger than that which would be usually provided for an aperture of such comparatively short length and illustrates approximately what would take place 40 during the course of the decay of a sound under the poorest conditions of our construction. Assuming that a sound wave "S" strikes the face of my material at any angle "X", the course of propagation is designated by the arrow points, and impacts against the side of the aperture and consequent absorption take place at A', A², A³, etc.

45 It will be seen that the sound entering the aperture will be partially absorbed at each successive impact. If total absorption takes place somewhere about the point "A²⁰" no sound will emerge from the aperture.

50 It will also be seen that by changing the width, length or number of apertures entering a given structural element can increase or decrease the sound-absorbing efficiency of the material.

55 It must not be supposed that sound-absorbing material of very high sound-absorbing capacity is necessarily better than material of lower sound-absorbing capacity. It frequently happens in practice, that a

60 room of large surface area requires only moderate sound-modification, in which case the absorbing capacity of the material must be reduced accordingly. Even the smallest and fewest apertures have some absorbing 65 power, and an almost infinite range of con-

trol is therefore possible through the use of surface apertures of various sizes and various distributions.

Fig. 3 shows an enlarged section 4 with the apertures 5 of another form of the material, said apertures containing felt 6, or other highly sound-absorbing material, in all or part of the aperture.

Fig. 3^a shows a construction similar to Fig. 3 with the difference that the apertures 5^a containing the felt or like material 6^a are closer together than the apertures 5 of Fig. 3.

Fig. 4 shows still another form 7 of the material, behind the surface of which is 80 felt or other highly sound-absorbing material 8, communicating with apertures 9 extending to one or more of the surfaces of said first-mentioned material.

Figs. 5 and 6 show the material formed in blocks 10 and 11 having in their interiors open spaces 12 and 13 communicating with the apertures 14 and 15, respectively.

It is understood that these apertures may vary greatly in width and may be arranged to present on the face of the material various designs to form a part of the decorative scheme of a room.

It will be understood that the principles of my invention may be carried out by forming the sound-absorbing apertures not only in blocks, sheets or other structural elements, but also in the surface of an already erected wall or ceiling. Thus a wall or ceiling may be coated with plaster in the usual way, and sharp points may be pressed against the plaster by means of a roller or other instrument; and such sharp points may make the necessary apertures either by mechanically puncturing the surface or by the chemical action of an acid or other reagent applied by the sharp points or otherwise.

It is well-known that mixtures of plaster of high porosity do not produce as much reverberation in a room as the harder non-porous forms. However, the number of cases of defective conditions for hearing in rooms covered with the more porous forms of plasters, demonstrate that they do not provide sufficient absorption for good acoustics.

In practice the formation of my long and narrow apertures in ordinary forms of plaster just before the plaster has set, is a cheap and practical way of obtaining the desired result and my invention covers just such condition. The apertures may, if desired, be arranged in various ornamental designs.

The materials described are preferably composed of plastic combinations of substances which are capable of being molded to various shapes, and which will take a final set and harden so as to be of substantial structural use. Such materials are gypsum, sand and cement mixtures, sand and lime

mixtures and the like, but the construction is not, of course, confined to these materials as almost any material constructed in the manner described would be highly sound absorbing.

In Fig. 7 is illustrated a further modification of my improved acoustic material. In this case the material may be in the form of a block 16 of plaster or the like which is 10 kerfed or slotted as at 17 to form longitudinal grooves. These grooves have the same sound deadening effect on the sound waves as the perforations in the above described constructions have.

Again in Fig. 8 is illustrated a further modification of the improved acoustic material which may consist of units or blocks 15 of corrugated flexible material, such as paper, fiber-board or the like, which is bent into convolutions 18 thus presenting at the outer 20 face grooves or passages such as 19 similar to the grooves 17 in the unit illustrated in Fig. 7. This corrugated material may have at the rear or one face, a backing strip or 25 sheet 20 by which the material is held together as a unitary structure.

In Fig. 9 is illustrated a still further modification in which layers or strips 21 of suitable material, such as paper, fiber-board, 30 cloth, felt or the like, may be laid together and secured to a backing member 22. The securing means may be cement or other suitable fastening means. The edges 23 of these strips or layers will necessarily present 35 spaces or grooves between them of greater or less width according to the character of the material used or the smoothness of the surfaces thereof, and these interstices between the layers will present sound deadening 40 cavities similar to those shown in the forms illustrated in Figs. 7 and 8.

In Fig. 10 is shown a further modification, the layers or strips 24 being suitably secured to the backing 25 may be still more separated 45 by means of particles 26 of fiber, sand or other suitable finely divided material, which will cause greater spacing apart of the layers or strips 24 than would result from the construction shown in Fig. 9.

It will be observed that the exposed surfaces shown in Figs. 9 and 10, particularly in Fig. 10, are not perfectly smooth, but are somewhat irregular. Such unevenness is often desired by architects and decorators, 50 and may readily be provided by my present materials, without destroying the definite absorbing power per unit area described above.

In Fig. 11 the strips or layers 27 may be 55 positively spaced apart in uniform manner by spacing strips 28, whereby interstices or sound absorbing apertures will be formed between the strips. Finally in Fig. 12 is illustrated a form of material in which the strips or layers 29 may be spaced apart by

short strips or blocks 30 which do not extend fully across the width of the strips 29, and which may be staggered in position, as illustrated to form more or less irregular openings or interstices for the absorption 70 of the sound. In this case it will be noted that the openings or interstices extending inward from the edges of the adjacent strips 29 will communicate with cross openings, such for example, as 31 between the ends 75 of the short spacing strips, and consequently the interstices extending inwardly from the edges of the material may also communicate one with the other.

The material also may be formed into 80 units of various sizes and of measurable sound-absorbing efficiency.

While I have herein described particular embodiments of my invention, it is understood that the same may be altered in many 85 details in relative arrangement of parts, in the manner and method of manipulating the acoustical elements and in the manner of applying and securing the same to or within the walls, ceilings or other surfaces, within 90 the scope of the patent claims.

What I claim is:

1. The method of establishing predetermined acoustic conditions for an enclosure that comprises providing in connection with 95 a boundary surface thereof a sound-absorbing material having apertures opening at the surface exposed to the sound waves, said apertures being of such number, dimensions and arrangement as to produce definite and 100 predetermined sound-absorbing capacity per unit area of the said exposed surface.

2. Sound-modifying material comprising a body having apertures mechanically and definitely formed therein and communicating with a normally exposed surface of said body, the said apertures being sufficiently numerous to have substantial sound-modifying effect, and said surface having definite and 110 predetermined sound-absorbing capacity per unit area of said surface.

3. Sound-modifying material comprising a body having apertures penetrating said body from a normally exposed surface thereof, said apertures being definite in 115 shape and sufficiently numerous to have substantial and predetermined sound-modifying effect, and each of the said apertures being of materially greater length than width.

4. Sound-modifying material comprising a non-refractory body adapted for use on the surface of walls, ceilings or other portions of an auditorium or enclosure, and having a series of similar sound absorbing apertures 125 penetrating said body from a normally exposed surface thereof, said apertures being of regular shape and sufficiently numerous to have substantial and predetermined sound-modifying effect, and each of the said 130

- apertures being of materially greater length than width. 40
5. Sound-modifying material comprising a non-refractory body adapted for use on the surface of walls, ceilings or other portions of an auditorium or other enclosure, and having a plurality of similar sound-absorbing apertures penetrating said body from a normally exposed surface thereof, said apertures being of regular shape and sufficiently numerous to have substantial and predetermined sound-modifying effect, and each of the said apertures being of materially greater length than width. 45
15. 6. A sound-modifying body having an internal cavity and having a plurality of similar apertures sufficiently numerous to have substantial and predetermined sound-modifying effect, the said apertures communicating, when the said material is in use, with the said internal cavity and with a normally exposed surface of said body. 50
25. 7. A sound-absorbing body having an internal cavity and having a plurality of regular and similar apertures sufficiently numerous to have substantial and predetermined sound-modifying effect, said apertures penetrating from a plurality of surfaces of said body, and communicating with the said internal cavity, each of the said apertures being of materially greater length than width and being of substantially uniform cross section. 55
35. 8. Sound-modifying material comprising a body adapted for use on the surface or within walls, ceilings or other portions of an auditorium or other enclosure, and having a series of regularly shaped sound absorbing apertures penetrating from a normally exposed surface of said material into said material, certain of said apertures containing fibrous sound-absorbing material, and said fibrous material and said apertures cooperating to produce predetermined sound-absorbing capacity per unit area of the surface with which said apertures communicate. 60
9. Sound-absorbing material for use on the surface or within walls, ceilings or other portions of an auditorium or other enclosure, having a series of similar sound-absorbing apertures of regular and definite shape penetrating from a normally exposed surface of said material into the said material, said apertures being sufficiently numerous to have substantial and predetermined sound-modifying effect, said surface having definite and predetermined sound absorbing capacity per unit area of said surface, and said material being constructed in units of various sizes and shapes of predetermined sound-absorbing efficiency and ready for application without the necessity of alteration. 65
10. The method of establishing predetermined acoustics for an enclosure that comprises the steps of providing the enclosure with surface material capable of receiving apertures, and then forming in the said material apertures communicating with the exposed surface of said material, the said apertures producing definite and predetermined sound-absorbing capacity in said material. 70
- In testimony whereof, I the said JACOB MAZER, have hereunto set my hand.
- JACOB MAZER.
